LIGHT SIGNAL

Arthur L. Jerome, Edgewood, Pa., assignor to
The Union Switch & Signal Company, Swiss-
vale, Pa., a corporation of Pennsylvania

Application May 1, 1943, Serial No. 485,374

8 Claims. (Cl. 177—337)

My invention relates to a light signal, and particularly to a signal capable of selectively projecting a plurality of beams of light from a single light source.

More particularly my present invention relates to a searchlight signal having a spectacle arm provided with red, yellow and green filters adapted to be selectively interposed in the signal beam to cause the signal to display stop, approach and clear indications.

An object of my invention is to provide novel means for operating the spectacle arm of a signal by two electromagnets so that the spectacle arm may be moved between its approach and its clear positions without passing through the stop position.

Another object of the invention is to provide a signal employing a first and a second electromagnet which are energized from a polarized control circuit in such manner that the first magnet checks operation of the second magnet and will not respond unless the second magnet correctly responds to the energy supplied over the polarized control circuit.

A further object of the invention is to provide an improved signal of the type described which is arranged so that the signal cannot display either its approach or its clear indication unless the first electromagnet responds to energy supplied over the control circuit to thereby insure that the signal will display its stop indication unless the signal is functioning as intended.

Another object of the invention is to provide a signal of the type described in which the first electromagnet is reversibly connected in series with the second electromagnet by means of continuity transfer contacts controlled by the second electromagnet so that the supply of energy to the second electromagnet is not interrupted during response of this magnet to energy supplied over the control circuit.

A further object of the invention is to provide an improved signal of the type described which is arranged so that the two electromagnets may both be energized from one polarized control circuit, or may be separately energized from different control circuits.

Another object of the invention is to provide improved means for energizing two electromagnets in series from a polarized control circuit.

Other objects of the invention and features of novelty will be apparent from the following description taken in connection with the accompanying drawing.

According to my invention, a vane or spectacle

arm carrying the color filters is biased by a counterweight or other means to one extreme position in which a red filter is disposed in the path of the light beam, while the vane is arranged to be moved from this position to the approach and clear positions by means of a floating lever connected with the vane. One end of this floating lever is connected to the armature of the first electromagnet and the other end of this lever is connected to the armature of the second electromagnet. The vane is connected with the floating lever at an intermediate point on the lever which is nearer the point of connection of the lever with the armature of the first electromagnet than the point of connection of the lever with the armature of the second electromagnet. The various elements of the signal are arranged so that when the armature of the first electromagnet is released the vane is held in a position in which a red filter is disposed in the path of the light beam irrespective of the position of the armature of the second electromagnet. The various elements of the signal are also arranged so that when the armature of the first electromagnet is picked up the vane is moved to the position in which the yellow or the green filter is interposed in the path of the light beam according as the armature of the second electromagnet is released or picked up.

I shall describe one form of signal embodying my invention together with a modification thereof of which I may employ, and shall then point out the novel features thereof in claims.

In the drawing Fig. 1 is a diagram of a signal embodying my invention, and

Fig. 2 is a view of a modification which I may employ.

Referring to Fig. 1 of the drawing the signal comprises a vane or spectacle arm 10 which is supported on a suitable pivot 11, and is provided with four color filters or roundels. These include a green filter G, a yellow filter Y, and two red filters R₁ and R₂, which are arranged to cooperate with a lamp 12. In the drawing the lamp 12 is shown above the filters for the purpose of illustration, but it is to be understood that in actual practice this lamp is located so that the filters are moved in front of the lamp as the spectacle arm is moved about the pivot 11. In addition it is to be understood that the lamp 12 may have associated therewith means, not shown, such as a reflector, for directing through the filter in front of the lamp the rays of light emitted by the lamp.

The spectacle arm 10 is connected by a pin 14 to the upper end of a link 15, while the lower end

of the link 15 is connected by a pin 16 to a floating lever 18. One end of the lever 18 is connected by a pin and slot connection 19 with the armature of the first magnet H, while the other end of the lever 18 is connected by a similar pin and slot connection 20 with the armature of the second magnet D.

The pin 16 connecting the link 15 with the lever 18 is located at a point on the lever 18 approximately twice as far from the point of connection of the lever 18 with the armature of magnet D as it is from the point of connection of the lever 18 with the armature of the magnet H. The various elements of the signal are arranged and proportioned so that when the armatures of the magnets H and D are both released the spectacle arm 10 is held in the position in which the red filter R1 is located in front of the lamp 12.

On picking up of the armature of magnet H the lever 18 pivots about the pin by which the lever is connected to the armature of magnet D while the pin 16 is lifted a distance substantially equal to two-thirds of the distance that the pin associated with magnet H is lifted. The various elements of the signal are proportioned so that on picking up of the armature of the magnet H, the spectacle arm 10 is moved about the pivot 11 a distance equal to two filters or roundels. Accordingly, when the armature of magnet H picks up when the armature of magnet D is released, the spectacle arm 10 is moved around the pivot 11 far enough to cause the yellow filter Y to be located in front of the lamp 12.

On picking up of the armature of the magnet D the lever 18 pivots about the pin 19 associated with the armature of magnet H, while the pin 16 is lifted a distance substantially equal to one-third of the distance that the pin 20 associated with the magnet D is lifted. The various elements of the signal are proportioned so that on picking up of the armature of magnet D the spectacle arm is moved about the pivot 11 a distance equal to one filter or roundel. Accordingly, when the armature of magnet D picks up when the armature of magnet H is picked up the spectacle arm is moved from the position in which the yellow filter Y is located in front of lamp 12 to the position in which the green filter G is located in front of the lamp 12, while when the armature of magnet D picks up when the armature of magnet H is released, the spectacle arm is moved from the position in which the filter R1 is located in front of lamp 12 to the position in which filter R2 is located in front of lamp 12.

In the drawing, the armatures of the magnets are shown in their released positions, while the picked up positions of these armatures are indicated by broken lines. In addition, broken lines extend between the ends of the armatures in their picked up and released positions to illustrate the effect of movement of the armatures on the pin 16, and therefore on the spectacle arm 10.

For convenience, each position of the pin 16 is designated by the reference character of the filter which is located in front of the lamp 12 in that position of the pin. When the armatures of both magnets are released, the pin 16 occupies its lowest position R1 in which the red filter R1 is located in front of the lamp 12. When the armature of magnet D is picked up and the armature of magnet H is released the pin 16 is lifted one unit to the position R2 so that filter R2 is located in front of the lamp 12. When the armature of magnet H is picked up and the armature of magnet D is released, the pin 16 is lifted two units to

the position Y in which the yellow filter Y is located in front of the lamp 12, while when the armatures of both magnets are picked up the pin 16 is lifted three units to the position G in which the green filter G is located in front of the lamp 12.

The magnet D is of a type the armature of which will pick up only when energy flows through the winding of the device from its left-hand to its right-hand terminal. The construction of the magnet D is not a part of this invention and this magnet may be constructed in any appropriate manner well-known in the art. One form of construction which may be employed is shown in Letters Patent of the United States No. 2,203,888, issued June 11, 1940, to H. E. Ashworth.

The windings of the magnets D and H are energized from a polarized control circuit over a circuit similar to that shown and claimed in application for Letters Patent of the United States, Serial No. 424,151, of A. E. Dodd. This circuit includes make-before-break contacts which are operated by the armature of the magnet D.

Either or both of the magnets D and H may have contacts operated by the armature of the magnet, as shown in the drawing, and these contacts may be employed in any appropriate manner.

Energy is supplied from a source of direct current, the terminals of which are designated + and -, to the windings of the magnets D and H. The polarity of the energy supplied from the source is governed by contacts 23 and 24 of a pole changer PC which may be governed by any appropriate condition, as for example, traffic conditions in advance of the signal. The supply of energy to the control wires is governed by a contact 25 which may be controlled in any desired manner.

The equipment is shown in the condition which it assumes when contact 25 is released so that the supply of energy to the windings of the magnets D and H is interrupted. As the windings of the magnets D and H are not energized the armatures of these magnets are moved by gravity or other means to their lower positions as shown so that force is exerted through the floating lever 18 and the link 15 to cause the spectacle arm 10 to occupy the position in which the red filter R1 is located in front of the lamp 12. Accordingly, the signal provides its red or stop indication.

On picking up of contact 25 when the pole changing contacts 23 and 24 are released, energy of reverse polarity is supplied to the control wires and flows through the windings of the magnets D and H over the circuit which is traced from the positive terminal of the source over contact 25, back contact 24, wire 27, asymmetric unit K1, winding of magnet H from left to right, contacts 28 and 29 of magnet D, winding of magnet D from right to left, wire 30, and back contact 23 to the negative terminal of the source.

The direction of flow of energy through the winding of magnet D is such that the armature of this magnet will not pick up, but remains released, so contacts 28 and 29 maintain the circuit traced above. The energy supplied through the winding of magnet H causes the armature of this magnet to pick up and thereby lift the right-hand end of the floating lever 18 so that force is exerted through the lever 18, and the link 15 to move the spectacle arm about the pivot 11 to the position in which the yellow filter Y is lo-

cated in front of the lamp 12. Accordingly, the signal now provides its yellow or caution indication.

If the contacts 23 and 24 are now picked up, the energy supplied to the control wires 27 and 30 is changed from reverse to normal polarity. On the supply of energy of normal polarity to the wires 27 and 30, energy flows from the positive terminal of the source over contact 25, front contact 23, wire 30, winding of magnet D from left to right, contacts 29 and 28, asymmetric unit K2, wire 27, and front contact 24 to the negative terminal of the source. The energy flowing through the winding of magnet D from left to right causes the armature of the magnet to be picked up with the result that contact 32 engages contact 29 and lifts it out of engagement with stationary contact 28.

When contact 32 engages contact 29 a circuit is established to connect the winding of magnet D across the control wires 27 and 30 in series with the winding of magnet H. This circuit is traced from the right-hand terminal of the winding of magnet D over contacts 29 and 32, winding of magnet H from left to right, and through asymmetric unit K2 to wire 27.

It will be seen, therefore, that on the supply of energy of normal polarity to the control wires 27 and 30 energy is supplied to the winding of magnet D over the circuit controlled by contacts 29 and 28, while on picking up of the armature of the magnet contact 32 engages contact 29 to establish the circuit for energizing the winding of magnet D in series with the winding of magnet H before contact 29 is moved out of engagement with contact 28. Accordingly, there is no interruption in the supply of energy to the winding of magnet D and the armature of this magnet is certain to complete its movement to its picked up position.

On the change in the energy supplied to the control wires from reverse to normal polarity the supply of energy to the winding of magnet H is interrupted until the armature of magnet D picks up. However, during the period in which the supply of energy to the winding of magnet H is interrupted the asymmetric units K1 and K2 provide a snubbing circuit for the winding of magnet H to thereby render the magnet slow to release with the result that the armature remains picked up during the period in which the supply of energy to the winding of the magnet is interrupted. After the armature of magnet D picks up the windings of magnets D and H are energized in series and the armatures of both magnets are held picked up.

On picking up of the armature of the magnet D when the armature of magnet H is picked up, the left-hand end of the lever 18 is raised and force is exerted through the lever 18 and the link 15 to move the spectacle arm 10 to the position in which the green filter G is located in front of the light 12 so that the signal displays its green or clear indication.

If, while energy of normal polarity is supplied to the control wires 27 and 30 and the armatures of both magnets are picked up, contact 25 is opened to cut off the supply of energy to the magnets D and H, the armatures of both magnets will release, while the spectacle arm 10 will be returned to the position in which it is shown in which the red filter R1 is located in front of the lamp 12.

If while energy of normal polarity is supplied to the control wires 27 and 30 and the armatures

of the magnets D and H are both picked up, the contacts 23 and 24 are released to change the energy supplied to wires 27 and 30 from normal to reverse polarity, the supply of energy to the windings of magnets D and H in series will be interrupted, while energy will be supplied to the winding of magnet D over the circuit traced from the positive terminal of the source over contact 25, back contact 24, wire 27, asymmetric unit K1, contacts 32 and 29, winding of magnet D from right to left, wire 30, and back contact 23 to the negative terminal of the source. Energy flowing through the winding of magnet D from right to left reverses the flux in the core of the magnet with the result that the armature of the magnet releases and thereafter remains released.

On movement of the armature of this magnet to its released position contact 32 is moved out of engagement with contact 29 to thereby interrupt the circuit just traced for energizing the winding of magnet D through the asymmetric unit K1, while contact 29 is moved into engagement with contact 28 to establish a circuit for energizing the magnet D in series with the winding of magnet H. This circuit is traced from the wire 27 through asymmetric unit K1, winding of magnet H from left to right, contacts 28 and 29, and winding of magnet D from right to left to wire 30. Accordingly, energy continues to flow through the winding of magnet D from right to left so the armature of this magnet remains released while energy is again supplied through the winding of magnet H from left to right to keep the armature of this magnet picked up. The winding of magnet H is snubbed by the circuit through the asymmetric units K1 and K2 during the period in which the supply of energy to the winding is interrupted so that the armature of the magnet remains picked up until energy is again supplied to the magnet winding.

On release of the armature of the magnet D while the armature of magnet H is picked up the left-hand end of the lever 18 is lowered so force is transmitted through the lever 18 and the link 15 to move the spectacle arm 10 to the position in which the yellow filter Y is located in front of the lamp 12.

If, while energy of reverse polarity is being supplied to wires 27 and 30 and the armature of magnet H is picked up to cause the signal to display its yellow or caution indication, the contact 25 is opened, the armature of magnet H will release and the spectacle arm 10 will be moved to the position in which red filter R1 is located in front of the lamp 12.

This signal is arranged so that if the armature of the magnet D picks up on the supply of energy of reverse polarity to the control wires 27 and 30 the signal will display its red or stop indication.

On the supply of energy of reverse polarity to the control wires when the armature of magnet D is released, energy flows from the positive terminal of the source over contact 25, back contact 24, wire 27, asymmetric unit K1, winding of magnet H, contacts 28 and 29, winding of magnet D from right to left, and back contact 23 to the negative terminal of the source. On flow of energy through the winding of magnet D from right to left, the armature of this magnet should not pick up, but if for any reason the armature does pick up and thereafter remains picked up, the circuit just traced for energizing the windings of magnets D and H in series will be interrupted because of disengagement of contact 29 from con-

tact 28, and a circuit will be established to connect the winding of magnet D directly across the control wires. This circuit is traced from wire 27 through asymmetric unit K1, contacts 32 and 29, and winding of magnet D from right to left, to wire 30.

The energy supplied to the winding of magnet D may maintain the armature of the magnet picked up, but as long as the armature remains picked up the winding of magnet H is shunted by asymmetric unit K1 and its armature releases and remains released. When the armature of magnet D is picked up and the armature of magnet H is released, the left-hand end of the lever 18 is lifted and force is exerted through the lever 18 and the link 15 to move the spectacle arm 10 to the position in which the red filter R2 is located in front of the lamp 12. Accordingly, when the armature of magnet D is improperly picked up, the armature of magnet H is released and the signal operates to provide a red or stop indication.

When energy of reverse polarity is supplied to the control wires 27 and 30 the armature of the magnet D will normally be released and the armature of magnet H will be picked up so the signal operates as explained in detail above to provide the yellow or caution indication. If for any reason the armature of magnet D picks up, the supply of energy to the winding of magnet H will be interrupted and its armature will release to thereby cause the signal to provide its red or stop indication.

It will be seen that the magnet H provides a check on operation of magnet D and the armature of magnet H will be released if the armature of magnet D is picked up at a time where energy of reverse polarity is supplied to the control wires. When the armature of magnet H is released the signal displays a red or stop indication regardless of the position of the armature of the magnet D. The operation of the signal, therefore, is such as to provide the maximum degree of safety since the signal will provide its stop indication unless the signal is functioning to provide the proper indication.

As pointed out above, on a change in the polarity of the energy supplied to the control wires 27 and 30, whether this change is from normal to reverse polarity or from reverse to normal polarity, the supply of energy to the winding of magnet H is interrupted until the armature of magnet D moves to a position in correspondence with the polarity of the energy supplied to the winding of the device. On interruption of the supply of energy to the winding of magnet H armature of this magnet is maintained picked up for a short period because of the snubbing circuit which exists for the magnet winding through the asymmetric units K1 and K2. This snubbing circuit for the magnet H serves to maintain the armature of the magnet picked up for a period long enough to enable the armature of the magnet D to respond to a change in the polarity of the energy supplied to the winding of magnet D. Since the armature of magnet H is maintained picked up on a change in the polarity of the energy supplied to the control wires, the spectacle arm 10 is moved between the yellow and green positions without moving to the red position as would occur if the armature of the magnet H should release. The operation of the signal, therefore, is such that changes between the yellow and green indications occur without momentary flashes of the red indication.

While the spectacle arm has been illustrated and described as being provided with two separate red filters, it is obvious that one filter large enough to extend in front of the lamp 12 in two positions of the spectacle arm, as shown in Fig. 2, might be employed instead.

Although I have herein shown and described only one form of signal embodying my invention, it is understood that various changes and modifications may be made therein within the scope of the appended claims without departing from the spirit and scope of my invention.

Having thus described my invention, what I claim is:

1. In a light signal, in combination, a spectacle arm carrying a first and a second red filter, a yellow and a green filter which are adapted to be interposed in a beam of light to cause the signal to provide red, yellow and green indications, a first and a second electromagnet each having an armature movable between a first and a second position, and means for operating said spectacle arm by the armatures of said electromagnet in such manner that when the armature of the first electromagnet is in its first position the first or the second red filter is interposed in the light beam according as the armature of the second electromagnet is in its first or its second position and so that when the armature of the first electromagnet is in its second position the yellow or the green filter is interposed in the light beam according as the armature of the second electromagnet is in its first or its second position.

2. In a light signal, in combination, a spectacle arm carrying a plurality of different filters which are adapted to be interposed in a beam of light to cause the signal to provide a plurality of different indications, said filters including a red and a green filter and a yellow filter disposed between said red and green filters to thereby permit the spectacle arm to be moved between the positions in which the green and yellow filters are interposed in the light beam without passing through the position in which a red filter is interposed in the light beam, a first electromagnet having an armature biased to a released position, a second electromagnet having an armature which is moved from a first to a second position when and only when energy flows through the winding of the electromagnet in a particular direction, a pair of control wires, means for at times supplying energy of one polarity and at other times supplying energy of the other polarity to said control wires, means including a contact governed by the armature of said second electromagnet for reversibly connecting the winding of said first electromagnet across said control wires in series with the winding of said second electromagnet, and means for operating said spectacle arm by the armatures of said electromagnets in such manner that when the armature of the first electromagnet is released a red filter is interposed in the light beam regardless of the position of the armature of the second electromagnet and so that when the armature of the first electromagnet is picked up the yellow or the green filter is interposed in the light beam according as the armature of the second electromagnet is in its first or its second position.

3. In a light signal, in combination, a spectacle arm carrying a plurality of different filters which are adapted to be interposed in a beam of light to cause the signal to provide a plurality of different indications, said filters including a red and a

green filter and a yellow filter disposed between said red and green filters to thereby permit the spectacle arm to be moved between the positions in which the green and yellow filters are interposed in the light beam without passing through the position in which a red filter is interposed in the light beam, a first electromagnet having an armature biased to a released position, a second electromagnet having an armature which is moved from a first to a second position when and only when energy flows through the winding of the electromagnet in a particular direction, a pair of control wires, means for at times supplying energy of one polarity and at other times supplying energy of the other polarity to said control wires, means including make-before-break contacts governed by the armature of said second electromagnet for reversibly connecting the winding of said first electromagnet across said control wires in series with the winding of said second electromagnet, and means for operating said spectacle arm by the armatures of said electromagnets in such manner that when the armature of the first electromagnet is released a red filter is interposed in the light beam regardless of the position of the armature of the second electromagnet and so that when the armature of the first electromagnet is picked up the yellow or the green filter is interposed in the light beam according as the armature of the second electromagnet is in its first or its second position.

4. In a light signal, in combination, a spectacle arm carrying a plurality of different filters which are adapted to be interposed in a beam of light to cause the signal to provide a plurality of different indications, said filters including a red and a green filter and a yellow filter disposed between said red and green filters to thereby permit the spectacle arm to be moved between the positions in which the green and yellow filters are interposed in the light beam without passing through the position in which a red filter is interposed in the light beam, a first and a second control conductor to which energy of normal polarity is supplied at times and to which energy of reverse polarity is supplied at other times, a first electromagnet having an armature biased to a released position and movable therefrom to a picked up position, a second electromagnet having its winding connected in series with one of said conductors and having an armature movable between a first and a second position, said second electromagnet being of a type the armature of which when in its first position is moved to its second position when and only when energy flows through the winding of said electromagnet from said first to said second conductor, means including make-before-break contacts governed by the armature of said second electromagnet and effective when said armature is released to connect said conductors together through an asymmetric unit poled to permit energy to flow from the second to the first conductor and to also connect said conductors together through the winding of said first electromagnet with the first conductor connected to a selected terminal of the winding of said first electromagnet and being effective when the armature of said second electromagnet is in its second position to connect said conductors together through an asymmetric unit poled to permit energy to flow from the first to the second conductor and to also connect said conductors together through the winding of the first electromagnet with the second conductor connected to said selected terminal of the winding of said first electromagnet, and

means for operating said spectacle arm by the armatures of said electromagnets in such manner that when the armature of the first electromagnet is released a red filter is interposed in the light beam regardless of the position of the armature of said second electromagnet and so that when the armature of said first electromagnet is picked up the yellow or the green filter is interposed in the light beam according as the armature of the second electromagnet is in its first or its second position.

5. In a light signal, in combination, a spectacle arm carrying a plurality of different filters which are adapted to be interposed in a beam of light to cause the signal to provide a plurality of different indications, said filters including a red and a green filter and a yellow filter disposed between said red and green filters to thereby permit the spectacle arm to be moved 15 between the positions in which the green and yellow filters are interposed in the light beam without passing through the position in which a red filter is interposed in the light beam, a first and a second control conductor to which 20 energy of normal polarity is supplied at times and to which energy of reverse polarity is supplied at other times, a first electromagnet having an armature biased to a released position and movable therefrom to a picked up position, 25 a second electromagnet having its winding connected in series with one of said conductors and having an armature movable between a first and a second position, said second electromagnet being of a type the armature of which 30 when in its first position is moved to its second position when and only when energy flows through the winding of said electromagnet from said first to said second conductor, means including make-before-break contacts governed 35 by the armature of said second electromagnet and effective when said armature is released to connect said conductors together through an asymmetric unit poled to permit energy to flow from the second to the first conductor and to 40 also connect said conductors together through the winding of said first electromagnet with the first conductor connected to a selected terminal of the winding of said first electromagnet and being effective when the armature of said 45 second electromagnet is in its second position to connect said conductors together through an asymmetric unit poled to permit energy to flow from the first to the second conductor and to 50 also connect said conductors together through the winding of the first electromagnet with the second conductor connected to said selected terminal of the winding of said first electromagnet, and means for operating said spectacle arm by the armatures of said electromagnets so 55 that when the armature of the first electromagnet is released and the armature of the second electromagnet is in its first position, the red filter is interposed in the light beam and so that when the armature of the first electromagnet is picked up the yellow or the green 60 filter is interposed in the light beam according as the armature of the second electromagnet is in its first or its second position.

6. In a light signal, in combination, a spectacle arm carrying a plurality of different filters which are adapted to be interposed in a beam of light to cause the signal to provide a plurality of different indications, said filters including a red and a green filter and a yellow filter disposed between said red and green filters

to thereby permit the spectacle arm to be moved between the positions in which the green and yellow filters are interposed in the light beam without passing through the position in which a red filter is interposed in the light beam, a first and a second control conductor to which energy of normal polarity is supplied at times and to which energy of reverse polarity is supplied at other times, a first electromagnet having an armature biased to a released position and movable therefrom to a picked up position, a second electromagnet having its winding connected in series with one of said conductors and having an armature movable between a first and a second position, said second electromagnet being of a type the armature of which when in its first position is moved to its second position when and only when energy flows through the winding of said electromagnet from said first to said second conductor, an asymmetric unit comprising a first and a second asymmetric element connected in series between a first and a second terminal and both poled to permit energy to flow from said first to said second terminal, the terminals of the winding of said first electromagnet being connected to the first and second terminals of said asymmetric unit, one of said control conductors being connected to an intermediate terminal of said unit intermediate said asymmetric elements, make-before-break contacts governed by the armature of said second electromagnet and effective according as said armature is in its first or its second position to connect the other control conductor to the first or the second terminal of said asymmetric unit, and means for operating said spectacle arm by the armatures of said electromagnets in such manner that a red filter is interposed in the light beam when the armature of said first electromagnet is released regardless of the position of the armature of the second electromagnet and so that when the armature of the first electromagnet is picked up the yellow or the green filter is interposed in the light beam according as the armature of the second electromagnet is in its first or its second position.

7. In a light signal, in combination, a spectacle arm carrying a first and a second red filter, a yellow and a green filter which are adapted to be interposed in a beam of light to cause the signal to provide red, yellow and green indications, a first and a second electromagnet each having an armature movable between a first and a second position, a floating lever supported at a first point by the armature of the first

electromagnet and supported at a second point by the armature of the second electromagnet, and means connected with said lever for moving said spectacle arm, said means being arranged so that when the armature of the first electromagnet is in its first position movement of the armature of the second electromagnet between its two positions causes the spectacle arm to be moved between the position in which the first red filter is interposed in the light beam and the position in which the second red filter is interposed in the light beam and also being arranged so that when the armature of the first electromagnet is in its second position movement of the armature of the second electromagnet from its first to its second position causes the spectacle arm to be moved from the position in which the yellow filter is interposed in the light beam to the position in which the green filter is interposed in the light beam.

8. In a light signal, in combination, a first and a second electromagnet each having an armature biased to a released position and movable therefrom to a picked up position, a floating lever supported at a first point by the armature of the first electromagnet and supported at a second point by the armature of the second electromagnet, a spectacle arm biased to a position in which it causes the signal to provide a stop indication and movable therefrom through a caution position in which it causes the signal to provide a caution indication to a clear position in which it causes the signal to provide a clear indication, said spectacle arm being operatively connected with said lever in such manner that when the armatures of both of said electromagnets are released the spectacle arm occupies its stop position, the point of connection of the spectacle arm with said lever, the amount of movement of the lever by the armatures of said electromagnets and the distance between the different positions of the spectacle arm being arranged and proportioned so that picking up of the armature of the first electromagnet will move the spectacle arm from the stop to the caution position and so that picking up of the armature of the second electromagnet will not move the spectacle arm from the stop to the caution position if the armature of the first electromagnet is released but will move the spectacle arm from the caution to the clear position if the armature of the first electromagnet is picked up.

ARTHUR L. JEROME.
